UNITED STATES PATENT OFFICE

CHARLES GILBERT HAWLEY, OF CHICAGO, ILLINOIS, ASSIGNOR TO CENTRIFIX CORPORATION, OF CLEVELAND, OHIO, A CORPORATION OF OHIO

CUPOLA

Application filed July 24, 1926. Serial No. 124,685.

The object of the invention is to provide improved and very simple draft effecting means for the better operation of cupolas and to provide a component structure adapted for successive employment with each of a series of cupolas or the like, at times of their respective operations; and, to keep the heat within reason; and which shall serve to catch and remove the dust that would 10 wear out the draft inducing mechanism and which, if not removed, would be thrown into the surrounding air to the annoyance and injury of neighboring persons and property.

The invention comprises and comprehends both the novel method and the novel draft inducing and dust collecting means herein-after detailed; and will be readily understood upon reference to the drawings that form part of the specification.

20 In said drawings, Fig. 1 is a vertical elevation of a cupola structure or the like, both illustrating and embodying the invention; and, Fig. 2 is a side elevation thereof.

As indicated in the drawing, the invention is adapted for use in connection with two or more cupolas or low stacks, marked A in the drawing. An elevated track B parallels the row of cupolas at one side thereof and preferably above the roof C of 30 the cupola house. On this track and for operation from end to end thereof is a car or trolley D which carries the dust collector proper E; also a suction fan F connected with the outlet of the collector E, and, suitable fan and trolley driving means, such as 35 the electric motor G.

Either the dust collector may have a bracket-like hood or cap to drop over the open top of the cupola; or, as preferred, each 40 cupola is provided with a hood or cap H. Each hood is suitably flanged, as at H', to meet and be connected with the flange E' belonging to the intake E'' of the dust collector E. The row of flanges H parallel the 45 track B, and the trolley D, being moved along the track, may be positioned to connect any one of the cupola hoods H with the dust collector E.

The cupola selected being in operation 50 and the collector being connected therewith

as described, the suction fan F is operated to induce, augment and regulate the draft through the cupola. Such use of the equipment is important from the standpoint of both increasing and nicely governing the 55 working capacity and the operation of the cupola.

Where the permanent stack tops or caps H are employed, each thereof should be provided with a door or vent opening K and a swinging door K', which may be opened when access is required to the top of the stack, or when it is desired to discharge the stack gases direct to the atmosphere, or more importantly, when it is desired to admit cold air across the top of the cupola for the purpose of markedly varying the draft and protecting the dust collector and blower from destructive heats in the cupola. The common smaller variations of draft are accomplished by varying the speed of the fan 70 motor, G.

As will be understood by those skilled in the art, the materials are charged into the cupola through the door in the side thereof, 75 above the charging floor; and, the combustion is maintained by air blast through tuyères (not shown) leading inward from the pressure air trunk, L, at the bottom of the cupola. The trunk is supplied with air 80 from a pipe M, which in turn receives the pressure air from the usual readily controlled and suitably valved blower system.

Attention has been called to the benefits that are secured by definitely measuring and 85 controlling the draft and which is now feasible by the employment of the heat-and-dust-protected suction fan. To these advantages must be added that of the effective regulation of the combustion by the control of the combustion air simultaneously with the control of the suction draft, whereby the melting capacity of the cupola can be greatly increased. And incidentally the temperature and pressure conditions at the charging door 90 may now be controlled to completely suppress the common annoying and dangerous flashing of the gases above the cupola charge. Further, because of the described admission 95 of cool air, the final heat or blowing down of 100

the charge may now be carried out without detrimentally overheating the cupola top or burning out the parts comprising the draft inducing equipment.

5 At one end of the elevated structure is a deep pocket I and when the collector has been filled with dust the trolley is run to that end of the structure and the collector E is emptied into the pocket I. From that point 10 the dust is disposed of by way of the valved down spout J, the dust usually being discharged into a waiting car.

Having thus described my invention, I claim as new and desire to secure by Letters 15 Patent:

1. A dust intercepting arrangement for stack tops, comprising, in combination with a row of intermittently used smokestacks, an elevated track paralleling the row thereof, 20 and at the top of the same, a dust collector movably positioned upon said track, means for connecting said collector first with one and then another of the stack tops, a suction fan movable with said collector, and driving means also movable therewith.

2. A dust intercepting arrangement for stack tops, comprising, in combination with a row of intermittently used smokestacks, an elevated track paralleling the row of stacks, 30 at the top thereof, stack caps of the same height, with relation to said track, a dust collector movable from stack to stack upon said track, means for connecting said collector with either said cap, a suction fan movable with said collector and having its intake connected therewith and suitable driving means movable with said collector and fan.

3. A stack, having a cap or hood at the top, and said cap being provided with a lateral offtake, in combination with a dust collector receiving the gases from said offtake, a suction fan drawing the gases through said collector, and means for admitting cool air across the entrance to said collector, for the protection of the same and the fan.

4. A dust intercepting and collecting arrangement for cupola tops comprising in combination with a row of intermittently operated stacks similarly constructed and of the same height, an elevated track paralleling said row and, at the top thereof, a dust collector movably positioned upon said track and thereby communicating first with one 55 and then another of the tops; a suction fan movable with said collector; and driving means also movable therewith.

5. A dust intercepting and collecting arrangement for cupola tops comprising in combination with a row of intermittently operated stacks similarly constructed and of the same height, an elevated track paralleling said row and, at the top thereof, a dust collector movably positioned upon said track 60 and thereby communicating first with one 65

and then another of the tops; a suction fan movable with said collector; means for drawing cooled air simultaneously with the smoke, and driving means also movable with said collector.

In testimony whereof I have hereunto set my hand this 23rd day of July, 1926.

CHARLES GILBERT HAWLEY.
